US00D919084S

(12) **United States Design Patent** (10) **Patent No.:** **US D919,084 S**
Alkmin et al. (45) **Date of Patent:** **** May 11, 2021**

(54) **ABSORBENT ARTICLE**

(71) Applicant: **Johnson & Johnson Consumer Inc.**, Skillman, NJ (US)

(72) Inventors: **Marco Antonio Alkmin**, Sao Paulo (BR); **Marcelo N. Pitta**, Sao Paulo (BR)

(73) Assignee: **Johnson & Johnson Consumer Inc.**, Skillman, NJ (US)

(**) Term: **15 Years**

(21) Appl. No.: **29/684,238**

(22) Filed: **Mar. 19, 2019**

(51) LOC (13) Cl. **24-04**

(52) U.S. Cl.

USPC **D24/125; D24/124**

(58) **Field of Classification Search**

(57) **CLAIM**

We claim the ornamental design for an absorbent article, as shown and described.

DESCRIPTION

FIG. 1 is a perspective view of an absorbent article according to an embodiment of the present invention;

FIG. 2 is a top plan view of the absorbent article according to the embodiment of FIG. 1;

FIG. 3 is a side view of the absorbent article according to the embodiment of FIG. 1;

FIG. 4 is a bottom plan view of the absorbent article according to the embodiment of FIG. 1;

FIG. 5 is an end view of the absorbent article according to the embodiment of FIG. 1;

FIG. 6 is a perspective view of an absorbent article according to a second embodiment of the present invention;

FIG. 7 is a top plan view of the absorbent article according to the embodiment of FIG. 6;

FIG. 8 is a side view of the absorbent article according to the embodiment of FIG. 6;

FIG. 9 is a bottom plan view of the absorbent article according to the embodiment of FIG. 6; and,

FIG. 10 is an end view of the absorbent article according to the embodiment of FIG. 6.

1 Claim, 6 Drawing Sheets
